POWDER DISPENSING DEVICE

Harold C. Moore, St. Louis, Mo., assignor of one-half to John J. Starr

Application May 18, 1936, Serial No. 80,310
Renewed March 10, 1938

4 Claims. (Cl. 221—66)

My invention relates to powder dispensing devices and more particularly to such devices for dispensing a cleaning powder in an elongated path on a tooth brush, hand brush or other similar cleaning implement wherein it is desirable that the powder be spread throughout the length of the brush.

Heretofore, in powder dispensing devices which have been made, the powder was allowed to flow from the container at one point only, that is, the powder was deposited at a single place relative to the length of the article receiving it. Therefore, such dispensing devices were ineffectual because, as explained above, to get full benefits the powder should be dispensed in an elongated path throughout the length of the brush in a single dispensing action. Furthermore, such devices as heretofore used have been intricate in design and construction with a resultant high cost of manufacture.

With these deficiencies of prior devices in mind, the objects of my invention are to provide a cleaning powder dispensing device which will be simple in design and operation; to provide such a device which may be easily refilled with the powder; to provide such a device which will have an inner container for the cleaning powder to be dispensed; and to provide a device wherein the powder will be dispensed in an elongated path.

While my invention may take various forms in different embodiments, I have shown herein as embodying my invention, a simple device combining a dispenser for tooth powder on a tooth brush and a holder for said brushes. In the accompanying drawings, Fig. 1 is a front elevation of the device; Fig. 2 is a side elevation; Fig. 3 is a partial section through the dispensing apparatus; Fig. 4 is a view of the device with some of the parts removed, as will be explained below; Fig. 5 is a section along the lines 5—5 in Fig. 1; and Fig. 6 is a transverse view of the parts shown in Fig. 4.

Referring to the figures, the combined tooth brush holder and powder dispensing device shown therein includes a horizontally arranged member 1 which may be secured to a wall by means of screws 2 or by any other suitable expedient and which carries on its face a plurality of hooks 3 each adapted to receive the perforation at the end of an ordinary tooth brush. If the member 1 is of an ornamental design, as shown in the drawings, the center section thereof is reduced or is otherwise formed to provide an attaching bar 4 as indicated in Figs. 4 and 5, spaced from the wall to which the member is fastened. The base

part 5 has outwardly extending flanges 6 along each side edge thereof and has near its upper end a flange 7 formed and arranged to engage the attaching bar 4 of the member 1. Also, a portion as at 8 of the base part is bent outwardly so that the device will be maintained in proper vertical position away from the wall. I prefer that the part 5 is extended downwardly, as shown in the figures, and then bent outwardly to provide a shield to catch powder which through accident and inadvertence is not deposited on the brush.

Attached to the base part 5 is a hopper 10 shaped to receive the open end of a container 11 for powder. Preferably, the bottom walls 12 of the hopper 10 converge downwardly so that the natural flow of the powder will be toward a sump formed by the walls. Fastened by any suitable means to the hopper 10 is the dispensing apparatus proper which consists, in this embodiment, of a fixed plate 13 arranged between adjacent ends of the bottom walls 12 of the hopper and having therein an aligned series of perforations 14. Slidably mounted on the upper surface of the fixed plate 13 is a movable plate 15 having an aligned series of openings 16 adapted to be registered by manipulation of said plate with the openings 14. The plate 15, in this embodiment, may be moved by pressure on a button 17 carried by a shaft 18 fixed to the movable plate. A spring 19 is arranged normally to hold the plate in a position in which the perforations 16 are out of register with the perforations 14. Preferably, the back vertical wall of the hopper 10 has an inwardly extending port to engage the end of the movable plate 16 and prevent powder from being packed between the end of the plate and the wall.

I prefer that an agitating device operated by manipulation of the dispensing device be provided and in the apparatus as shown such agitating device comprises a series of short pins 20 extending vertically upwardly from and preferably at right angles to the movable plate 15. While the pins 20 may be mounted at any points on the plate 15, I prefer that they be mounted in the space between adjacent holes 16, as shown in Figs. 3, 5 and 6 and for the purposes more fully outlined below.

A decorative hood or shield 21 may be provided to cover the container 11 and other parts and to give a finished and attractive appearance to the device. Preferably, the cover has knobs 22 formed in the marginal side edges thereof which knobs have a spring fit with indentations 23 formed in the flanges 6.

The operation of the embodiment of my device as described above, is as follows:—

The brush on which the cleaning powder is to be dispensed is held below the elongated outlet 24 from the dispenser. The button 17 is pressed inwardly and moves the plate 15 into a position wherein the openings 16 register with the openings 14 in the fixed plate 13. Powder will then flow through said openings onto the brush in an elongated path so that the entire length of the brush is covered. If the powder becomes caked or set in the hopper 10 the pins 20 moving with the plate 15 will agitate the powder and assure a free flow through the openings. While powder may be dumped in the hopper which may be of any size, I prefer that, as stated above, the hopper be shaped to receive the open end of a can or other container 11, preferably, the container in which the powder is marketed by the manufacturer thereof. Sometimes it will be necessary in putting a new and full container in the device to remove the device from the member 1, turn it upside down and then after removing the hood 21 insert the container 11 in place before the device is again inverted and put back in place.

It should be understood that although I have shown in the accompanying drawings one embodiment only of a dispensing device made according to my invention I do not intend to limit myself to the exact form shown and described, because the size, shape, construction and arrangement of the various parts may be changed within wide limits without deviating from the spirit of my invention and without departing from the ambit of the appended claims.

What I claim as new and desire to secure by Letters Patent, is:—

1. A powder dispensing device comprising a base part adapted and arranged to be supported on a wall, said base part having mounted thereon a hopper for powder, said hopper being arranged to receive a powder container and having an

elongated path through which powder may flow therefrom, means for controlling the flow of powder from said hopper, and a hood detachably secured to said base part and arranged to conceal said hopper and said container.

2. A powder dispensing device comprising a base part adapted and arranged to be supported on a wall, said base part having secured thereto a hopper for powder, said hopper having its upper walls adapted to receive the upper end of a powder container and having an elongated path through which powder may flow therefrom, manually operable means for controlling the flow of powder from said hopper, and a hood detachably secured to said base part and arranged to conceal said hopper and said container.

3. A powder dispensing device comprising an attaching member adapted to be secured to a wall, a base part detachably secured to said attaching member, said base part having mounted thereon a hopper for powder, said hopper being arranged to receive the open end of a powder container and having an elongated path through which powder may flow therefrom, means for controlling the flow of powder from said hopper and a hood detachably secured to said base part and arranged to conceal said hopper and said container.

4. A powder dispensing device comprising an attaching member adapted to be secured to a wall and having a plurality of hooks formed thereon, a base part detachably secured to said attaching member, said base part having mounted thereon a hopper for powder, said hopper being arranged to receive the open end of a powder container and having an elongated path through which powder may flow therefrom, means for controlling the flow of powder from said hopper and a hood detachably secured to said base part and arranged to conceal said hopper and said container.

HAROLD C. MOORE.
